(57) **CLAIM**

The ornamental design for a water bottle, as shown and described.

DESCRIPTION

FIG. 1 is a perspective view of a water bottle showing the new design;

FIG. 2 is a side view thereof;

FIG. 3 is a side view thereof, opposite of FIG. 2;

FIG. 4 is a front side view thereof;

FIG. 5 is a back side view thereof, opposite of FIG. 4;

FIG. 6 is a top view thereof; and,

FIG. 7 is a bottom view thereof.

The broken lines showing environmental structure depict unclaimed portions of the water bottle and form no part of the claimed design.

1 Claim, 6 Drawing Sheets
